BARBECUE UNIT

Stanley M. Joseph, Burbank, Calif.

Application February 21, 1958, Serial No. 49,746

Term of patent 14 years

(Cl. D81—10)

FIG. 1.

FIG. 2.

Fig. 1 is a perspective view of the top, front and one side of a barbecue unit showing my new design; and
Fig. 2 is a perspective view of the top, rear and one side thereof.

The side of the barbecue unit opposite that shown in the drawing is the same as the side shown.

I claim:

The ornamental design for a barbecue unit, substantially as shown and described.
